UNITED STATES PATENT OFFICE.

JOHN A. KOCH, OF ROSEDALE, KANSAS.

HARMONIC PLAYER FOR KEYBOARD INSTRUMENTS.

1,085,140.

Specification of Letters Patent.

Patented Jan. 27, 1914.

Application filed June 20, 1911. Serial No. 634,274.

To all whom it may concern:

Be it known that I, JOHN A. KOCH, a citizen of the United States, residing at Rosedale, in the county of Wyandotte and State 5 of Kansas, have invented certain new and useful Improvements in Harmonic Players for Keyboard Instruments, of which the following is a specification.

My invention relates to improvements in 10 accompaniments for vocal or instrumental music, and my object is to provide an apparatus of this character whereby a plurality of musical instruments may be operated either separately or simultaneously in 15 accompanying a leading part rendered vocally or instrumentally.

The device, in its preferred form, is arranged to be operated with the feet, so that 20 both hands may be free to operate a wind or string instrument with which the leading part may be rendered.

In its present form the apparatus is arranged for playing a piano, a bass-drum, a cymbal, and a snare-drum, although other 25 musical instruments may be added or substituted to suit the convenience of the player.

In order that the invention may be fully understood, reference will now be made to the accompanying drawings, in which:

30 Figure 1 shows an elevation of my improved apparatus. Fig. 2 is a plan view of the same with the bass and snare-drums removed. Fig. 3 shows an elongated pedal and an equalizer therefor, employed in controlling 35 the snare-drum. Fig. 4 shows an electric circuit to actuate the snare-drum stick. Fig. 5 is a plan view of a group of devices for actuating certain keys of a piano. Figs. 6 and 7 are sectional views taken, respectively, 40 on lines VI—VI and VII—VII of Fig. 5. Fig. 8 is a detail perspective of one of the devices for actuating certain piano keys. Figs. 9 and 10 are enlarged vertical sections 45 taken on lines IX—IX and X—X, respectively, of Fig. 1. Fig. 11 is a detail of one of four legs for supporting a main frame, employed in carrying out the invention. Fig. 12 is a detail section on line XII—XII of Fig. 10.

50 In carrying out the invention, I employ a main frame 1, consisting substantially of four supporting members 2, transverse pieces 3 uniting the upper ends of said supporting members, and longitudinal pieces 4, 4^a and 4^b, connecting said transverse pieces. Frame 1 carries practically the entire apparatus,

and is portable so that the apparatus may be moved into proper relation with the keyboard A, of a piano, or removed to some point where it will be out of the way when 60 not in use.

Frame 1 is vertically-adjustable through the intermediacy of a plurality of legs 5, so that the key-strikers hereinafter referred to, may be brought into proper vertical relation with the key-board A. This vertical adjustment is had by raising or lowering legs 5 as required, after which they are reliably secured in place by thumb-nuts 6 and bolts 7, the hook-shaped ends of which latter are drawn tightly into engagement with the notched edges 8 of the legs.

9 designates a pedal key-board for actuating two groups of key-strikers 10 and 11, which control certain keys of the piano. 75 The pedal key-board 9 consists of a horizontal row of pedals 12, each of which has a downturned forward end 13, fulcrumed in a socket in a rail 14, extending longitudinally of frame 1. The forward 80 ends of the pedals 12 are held in their sockets by a cap 15, removably-secured to rail 14 by screws 16, and to avoid any noise incidental to the operation of the pedals 12 in their sockets, the latter are lined with cushions 17 of felt or other material, which also extends between the pedals and the cap 15. Upward movement of pedals 12 is limited by a rail 12^a, provided at its underside 85 with a cushion 12^b to obviate any noise incidental to checking the upward movement of the pedals.

The key-strikers comprising groups 10 and 11 are substantially identical in construction, each consisting of a lever 18, a cross-bar 19 fixed to the downturned forward end of lever 18, and a plurality of cushioned fingers 20 depending from cross-bar 19. The rear downturned ends 21 of levers 18 are fulcrumed in sockets in the longitudinal 95 piece 4^a of the main frame 1, where they are secured by longitudinal caps 22, cushions 23 being interposed between the walls of the sockets, the caps, and the downturned ends 21, to obviate any noise incidental to the 100 operation of levers 18. The cross-bars 19 of the respective groups 10 and 11 are arranged as closely together as possible (see Figs. 1 and 5) to avoid material differences in the lengths of levers 18, each of which 110 engages its respective cross-bar 19 as near the center of resistance as possible, so that

when said cross-bar is forced downward, the fingers 20 will engage and force the underlying piano keys downward an equal distance. To avoid spreading the cross-bars 19 unduly apart, one or more of said cross-bars may be provided with forwardly extending fingers 20^a, as shown in Figs. 5 and 6, for manipulating the underlying short black keys *a* of the key-board A.

10 The two groups of key-strikers 10 and 11, are actuated by the pedals 9 through the intermediacy of two groups of connecting wires 24 and 25, respectively, the upper ends of which are connected to their respective 15 levers 18, about equal distances from the cross-bars 19, (see Fig. 5). Thus when the pedals are depressed equal distances, notes of similar volume will be produced instead of notes of different volume, as would be the case 20 if the distances between the cross-bars 19 and the connecting points of the wires with their respective levers 18, were unequal. The wires 24 and 25 are run in a vertical plane 25 as nearly as possible to avoid undue side draft on the levers 18, and since the levers 18 in group 10 are more closely arranged than those in group 11, I connect a number of the wires 24 to crank-arms 26, fixed to superimposed rock-shafts 27, carrying a plurality 30 of crank-arms 28, similar to crank-arms 26, and from which short wires 24^a extend to the underlying pedals 12. Rock-shafts 27 are mounted in a pair of standards 27^a. Each crank-arm 26 has a wire 24 connected thereto, and each crank-arm 28 has a wire 24^a connected thereto.

When the key-strikers are drawn downward by depressing pedals 12, they, together with the pedals, are restored to normal by 40 resilient means 29, when downward pressure on the pedals is removed. Said resilient means 29 consists, preferably, of elastic bands, each of which passes beneath its respective lever 18 and around a pin or screw 45 30, projecting from a bridge 31 spanning the levers 18, and secured at its downturned ends to the transverse piece 4^b of frame 1. Upward movement of levers 18 is limited by regulating-screws 32, adjustably engaging extension 33 of bridge 31, and provided 50 at their lower ends with cushions 34 to prevent noise from the impact of the levers 18.

Vertical guides 35 extending upward from 55 piece 4^b and engaging the sides of levers 18 prevent any lateral movement of said levers which might otherwise be imparted thereto by the more or less side draft exerted thereon by the connecting-wires 24 and 25. Pedals 60 12 are also held against lateral movement due to the side draft of the connecting-wires, the means employed being a longitudinal piece 12^c, having fingers 12^e, between which the levers extend.

65 36 designates a foot-rest extending across

the lower portion of the frame 1, just in the rear of the pedal-board 9, so that the pedals may be operated by the toes while the heels are resting upon the foot-rest. Said foot-rest is supported by a pair of cushions 37, 70 and a cushion 38, cushions 37 resting upon a cross-rail 39. When desired, foot-rest 36 may be removed to gain access to the adjacent mechanism, or it may be raised to suit the convenience of the player by placing 75 other cushions beneath cushions 37 and 38.

41 designates an auxiliary frame secured by hinges 42, to one end of main frame 1, and having a hinged joint 43, so that it may be folded against frame 1. Frames 1 and 41 are provided with eye-bolts 44 and 45, respectively, to which the ends of a pair of cables 46 are attached, said cables and frames forming a cradle for the reception of a bass-drum B, which is reliably secured in position in said cradle by hooks 47 and 48, carried by frame 1, and engaging eye-bolts 49 and 50, respectively, on the drum.

C designates a cymbal secured to the rim of drum B, by a lug *c*. Drum B and cymbal *c* are simultaneously sounded by a beater consisting of an elongated pedal 51, a pair of connecting-wires 52, a lever 53, a drum-stick 54 and a cymbal-stick 55 secured to the drum-stick. Pedal 51 is arranged between the key-board 9 and the foot-rest 36, so that it may be actuated with said pedals when desired, and it is held from lateral or longitudinal movement by a pair of guide-pins 56 extending through two holes 57 in a rail 58, secured to the lowermost transverse pieces 3. Lever 53 is fulcrumed on a screw 59 extending through a cushioned-hook 60, removably-mounted in a holder 61, secured to the adjacent end of frame 1. Drum-stick 54 is operatively connected to the outer end of lever 53 by a connecting-bar 62, and is pivotally-secured to the looped end of a bracket 63, secured to the rim of drum B and terminating in a cushioned stop 64, against which the cushioned lower end 65 of the drum-stick impinges when said drum-stick swings backward from the drum, which movement is quickly accomplished by an elastic band 66, 110 extending around the lower portion of the drum-stick and secured to the rim of drum B.

67 designates a saddle secured to one end of frame 1, to support a snare-drum 68, which is sounded by a beater comprising a drum-stick 69, an electric circuit 70, and an elongated pedal 71, arranged between the key-board 9 and the foot-rest 36, so that it may be operated with said key-board when desired. Drum-stick 69 is fixed to 120 the armature of an electromagnet 72, said armature being normally held out of contact with the magnet by a retractile spring 73. Magnet 72 is supported by a depending bracket 74 fixed to the rim of the snare- 125 130

drum 68. Circuit 70 derives current from a battery 70^a, and is normally held open by a circuit-breaker consisting of a stationary contact 75, fixed to rail 58, and a movable contact 76 fixed to pedal 71, which pedal is normally held in raised position by a coil-spring 77, fixed at its ends to the pedal and an equalizer 78 secured to the pedal and frame 1, for the purpose of maintaining said pedal in a horizontal position irrespective of whether pressure be applied to the center or either end thereof.

Having thus described my invention, what I claim, and desire to secure by Letters Patent, is:

1. In combination with a drum and a piano, a main frame adapted to be placed in juxtaposition with said piano, a plurality of key-strikers mounted upon said main frame and adapted to actuate the keys of the piano, a pedal key-board operably mounted upon the main frame to actuate said key-strikers, and an auxiliary frame to coact with the main frame in supporting the drum, said auxiliary frame being hinged to the main frame, against which it is adapted to fold.

2. In an apparatus for actuating the key-board of a musical instrument, a plurality of key-strikers, each including a pivotally-mounted lever, a bridge extending over the levers, resilient means engaging said bridge and the levers to normally hold the latter in raised position, cushioned means adjustably-engaging the bridge to limit upward

movement of the levers, means to depress the levers against the action of the resilient means, and vertically-extending guides to prevent lateral movement of the levers.

3. In an apparatus for playing the keys of a musical instrument, a frame having legs resting upon the floor, standards mounted on said frame, a horizontally extending rock-shaft journaled in said standards, two crank-arms fixedly mounted on said shaft, a key-striker lever mounted on the upper part of said frame, a wire connecting said lever with one of said crank-arms, a pedal mounted on said frame below said shaft, and a wire operatively connecting the pedal with the other crank-arm on said shaft.

4. In an apparatus for playing the keys of a musical instrument, a frame having legs resting upon the floor, standards mounted on said frame, a bank of superimposed rock-shafts journaled in said standards, crank-arms fixedly mounted on each of said shafts, key-striker levers mounted on the upper part of said frame, wires connecting said levers with crank-arms of different rock-shafts, pedals mounted beneath the rock-shafts, and means connecting each pedal to a crank arm.

In testimony whereof I affix my signature, in the presence of two witnesses.

JOHN A. KOCH.
